FISH LURE

Conrad Wood, El Dorado, Ark., assignor to James Heddon's Sons, Dowagiac, Mich., a corporation of Michigan

Application February 10, 1958, Serial No. 49,561

Term of patent 14 years

(Cl. D31—4)

Figure 1 is a side elevational view of a fish lure, embodying my new design;

Figure 2 is a top plan view thereof;

Figure 3 is a bottom plan view of Figure 1;

Figure 4 is a front elevational view of Figure 1, the hooks being broken away for convenience of illustration; and

Figure 5 is a rear elevational view of Figure 1, the hooks being broken away for convenience of illustration.

The characteristic features of the lure reside in the portions shown in solid lines.

I claim:

The ornamental design for a fish lure, as shown and described.
